UNITED STATES PATENT OFFICE

2,187,553

STAY FOR DOORS OF MOTOR VEHICLES
AND THE LIKETrevor Howard Butchart, Auckland, Auckland,
New ZealandApplication June 8, 1938, Serial No. 212,590
In New Zealand October 15, 1937

3 Claims. (Cl. 292—275)

The invention relates to stays for doors of automobiles and the like, which are used in such positions that said doors when released from the fastenings usually fitted to keep them closed, are unable to remain in a desired position owing to the inclination or slope of the door mountings which is responsible for said doors swinging either to the fully open, or the fully closed position according to the inclination or slope of the door mounting.

The object of the invention is to provide for use between a pillar or the like from which a door is hung and said door, an improved form of stay capable of being adjusted and set to hold the door in a desired position.

The improved stay provided by the invention comprises a rod pivotally attached at one end to the fixture from which the door is hung; a plate mounted to travel on the door and having the other end of said rod pivotally connected therewith, and means for regulating travel of said plate.

In the accompanying drawing, in conjunction with which the invention will be more particularly described—

Figure 1 is a part elevation showing the improved stay fitted to a door and adjusted to hold the latter in a partly open position.

Figure 2 an elevation of the parts appearing in Figure 1, but showing the stay in the position it occupies when the door is closed.

Figure 3 a sectional plan view of the plates which are mounted on the door.

Figure 4 a detail view illustrating an alternative way of connecting the rod of the stay with the plate adapted to travel on the door, and

Figures 5 and 6 part elevations illustrating different positions of the travelling plate when same is pivotally mounted.

The stay comprises a rod 1 pivoted at one end between lugs 2 on a plate 3 secured to a fixture, such as the pillar 4, from which the door 5 is hung in usual manner, said lugs 2 projecting from the face of the pillar 4 against which the door closes, an opening 6 in the door enabling the latter to pass upon the lugs 2 and also accommodating the rod 1.

At its other end the rod 1 is connected to the outer end of a plate 7 mounted to travel between the doubled portions of a plate 8 secured through one of said portions to the inside of the lining or inner surface of the door 5, the outer end of the plate 7 being offset to lie in the same plane as the portion of the doubled plate 8 re-

moved or distant from the lining or inner surface of the door.

As shown in Figures 1 and 2, the plate 7 is 5
slidable in the doubled plate 8, a screw pin 9
which is passed through a plain hole 16 in the
portion of the plate 8 secured to the door 5 and
is entered in a screw threaded hole 17 in the
other or inner portion of the plate 8 also pass- 10
ing through a slot 7a in the plate 7 and having
on its end located at the inner side of the door 10
5, a flange 18 and a handle 19 by means of which
the screw pin 9 can be turned to draw the two
portions of the doubled plate 8 together and so
clamp or grip between them the plate 7 to pre- 15
vent movement thereof.

When the door 5 is fully closed, the stay occupies the position illustrated in Figure 2 with the plate 7 pushed right in between the doubled portions of the plate 8, and as said door is opened, the rod 1, owing to its being attached to the 20
pillar 4, causes the plate 7 to be drawn outwards
between the doubled portions of the plate 8 ac-
cording to how far the door is opened, and the
latter may be retained in any desired open pos- 25
ition by turning the screw pin 9 to cause the plate 7 to be gripped between the doubled portions of 15
the plate 8.

The rod 1 can be provided with a fork 11, and be pivoted as at 12 to the plate 7, or the latter can have fitted thereto a socket 13 to take a ball 30
14 on the end of the rod 1, so that a ball and
socket joint is provided between the rod 1 and
the plate 7.

Also the hole 1a in the rod 1 at its end at- 35
tached to the pillar 4, is made somewhat larger
than the pivot pin passed therethrough, and the
space between the lugs 2 is made sufficient to per-
mit the end of the rod 1 to rock on the pivot
pin between the lugs 2 and similarly the holes 40
in the fork 11 are made larger than the pivot
pin 12 and increase in diameter outwards while
sufficient space is left between the legs of the
fork 11 to permit the latter to rock on the pin 12.

The play or rocking allowed in the joints just 45
described, is provided to overcome slight mis-
alignment of or inaccuracies in fitting the vari-
ous parts, the ball and socket joint, when used,
also assisting in overcoming misalignment or
inaccuracies.

Instead of the plate 7 sliding in the doubled 50
plate 8, it can be pivoted therein by the screw
pin 9, the rod 1 being connected to the lower off-
set portion of the plate 7 which as the door 5 is
opened and closed, swings on the pin 9, said
plate 7 being locked as before by being gripped 55

between the two portions of the doubled plate 8.

Pivotal movement of the plate 7 about the screw pin 9 in both directions is limited by a stop 15 on said plate 7 engaging the lower edge of the portion of the doubled plate 8 secured to the door 5, the lower edge of said plate portion being cut away as shown to permit the requisite movement of the plate 7.

- 10 The doubled plate 8 can be compressed to grip the plate 7 and hold the door 5 against movement on its hinges, or it can be set to act as a check or brake on opening and closing movement of the door, or it can be released to allow the door 5 to swing on its hinges without hindrance, and be compressed only when required to retain the door 5 in a desired open position.
- 15 When the sliding plate 7 is used, the slot 7a in the latter works on a guide pin 8a on the plate 8, said pin 8a and the screw pin 9 maintaining the plate 7 in the correct position for operation.

What I do claim and desire to obtain by Letters Patent of the United States of America is:

- 20 1. A stay for hinged doors, comprising a bracket attached to the fixture from which the door is hung, a rod pivotally connected at one end to the bracket and arranged through an opening in the inner edge of the door, a plate doubled upon itself and secured within the door, a second plate member movably mounted between the bent portions of the plate member and provided with an offset portion at one end thereof, manually operable means on the door for releasably clamping said second plate member in any desired position between the bent portion of the said first mentioned plate member, and a connecting rod operatively connected at one end to the offset portion of the said second mentioned plate member and at the other end to the bracket on the door post.
- 25 2. A stay for hinged doors, comprising a bracket attached to the fixture from which the door is hung, a rod pivotally connected at one end to the bracket and arranged through an opening in the inner edge of the door, a plate doubled upon itself and secured within the door, a second plate member bent upon itself and secured within the door, another plate having a slot therein mounted to slide between the portions of the doubled plate and having an offset portion at the outer end thereof operably connected to the other end of the rod; a flanged screw pin passed through said doubled plate and the slotted plate to provide means for compressing said doubled plate on the slotted plate, and a handle on said screw pin.
- 30 3. A check for holding an auto door in the desired position relative to a door post including a bracket on the post, the door having an aperture provided on its inner end adjacent the door post and adapted to receive the bracket, a plate member bent upon itself and secured within the door, a second plate member movably mounted between the bent portions of the plate member and provided with an offset portion at one end thereof, manually operable means on the door for releasably clamping said second plate member in any desired position between the bent portion of the said first mentioned plate member, and a connecting rod operatively connected at one end to the offset portion of the said second mentioned plate member and at the other end to the bracket on the door post.

35 TREVOR HOWARD BUTCHART.
